(57) **CLAIM**

The ornamental design for a livestock collar as shown and described.

DESCRIPTION

FIG. 1 is a top perspective view of a livestock collar, showing my new design;

FIG. 2 is a front elevation view thereof;

FIG. 3 is a rear elevation view thereof;

FIG. 4 is a side left view thereof;

FIG. 5 is a side right view thereof;

FIG. 6 is a top view thereof;

FIG. 7 is a bottom view of the livestock collar of FIG. 1 shown in an alternate configuration not attached to a strap; FIG. 8 is the bottom view thereof, showing a section of a strap used to fasten the livestock collar to a livestock, for illustration purposes;

FIG. 9 is a front, perspective view thereof, shown in an alternate configuration bent downward as if worn by livestock; and,

FIG. 10 is another front perspective view thereof, shown fastened and in condition of use on a livestock.

The broken line outline of livestock in FIG. 10 represents environmental subject matter that forms no part of the claimed design. The remaining broken lines shown in the drawings represent portions of the livestock collar that form no part of the claimed design.

1 Claim, 10 Drawing Sheets
